UNITED STATES PATENT OFFICE

2,379,086

FURNITURE SPRING CONSTRUCTION

William A. Kalpakoff, Walnut Park, Calif., assignor to Percy Solotoy, Los Angeles, Calif.

Application November 23, 1942, Serial No. 466,564

2 Claims. (Cl. 155—179)

The present invention relates generally to articles of furniture, such as chairs, settees, dayports and the like, of a character in which upholstery and upholstery pads overlie spring supports in either or both the seats and backs, and more particularly to such spring supports with the primary object of providing a simple, effective and efficient arrangement capable of being substantially entirely produced of wood as a substitute for the usual helical metal springs commonly heretofore used.

It is a further object of the invention to provide a spring support of the above type which may be completely pre-formed apart from the article of furniture and subsequently readily and effectively anchored therein to serve either as a seat support or a back support, or both, and in which a pair of rails are floatingly supported at the opposed ends of spring members, and connected by a series of upholstery supporting slats which are mounted to have relatively lengthwise movement with respect to at least one of said rails.

In the accompanying drawing, which illustrates the preferred form of the invention, and forms a part of this specification,

Fig. 1 is a vertical longitudinal sectional view through a chair frame, illustrating the practical application of the invention in connection therewith.

Fig. 2 is a horizontal sectional view, looking downwardly upon the seat frame, along the line 2—2 of Fig. 1, and

Fig. 3 is a detail perspective view of one of the yieldingly supported floating rails particularly showing the arrangement for the movable support of the adjacent ends of the upholstery supporting slats.

Referring to the above described figures, in Figs. 1 and 2 the frame of a chair or similar article of furniture is shown as comprising a horizontal seat frame including front and rear cross members 10 and 11 and side members 12 and 13, and a back frame including corner uprights or posts 14 connected by an upper cross member 15. This showing is merely intended to exemplify a conventional frame for an article of furniture of the over-stuffed type in which spring means serve as a yielding support for the upholstery and upholstery pads.

The yielding upholstery support of the present invention, intended as a substitute for the usual helical metal springs, essentially comprises a pair of spaced parallel rails floatingly supported by connection on the outer ends of supporting

spring slats whose inner ends abut one another and are securely anchored in the chair frame so that the spring slats may extend at an angle with respect to one another toward the rails floatingly supported thereby. This arrangement of spring slats yieldingly holds the rails from one side thereof, leaving the other side of the rails for connection by a series of slats in parallel more or less closely spaced relation to form with the rails an upholstery supporting surface, the latter slats being movable lengthwise thereof with respect to at least one of the rails.

Thus, as best seen in Fig. 1 the spring supporting structure for the seat frame, may consist of front and rear rails 16 and 17 fixed on the upper outer ends of side spring slats 18 and 19. These spring slats which are disposed in angular relation to each other, are supported at their lower abutting inner ends on anchor blocks 20 which may be screwed or otherwise fastened to the frame side members 12 and 13, fastening screws being seen at 21. The outer end of spring slats 18 and 19 may be connected to the lower surfaces of rails 16 and 17 by screws or similar fastening members 22, and may each consist of a long main leaf 23 and shorter supplemental leaves 24 and 25.

While the lower inner ends of spring slats 18 and 19 may be desirably secured to the anchor blocks 20, it is preferable that they rest upon angular upper surfaces of such blocks and be held by overlying cap blocks 26, fastening screws and the like 27 being driven down through the cap blocks and spring slats into the anchor blocks, as plainly seen by a comparison of Figs. 1 and 2.

To the upper surface of the front rail 16, which in practice may be spaced above, and parallel with, the front frame member 10, are preferably secured the forward ends of a series of resilient upholstered supporting slats 28, laterally spaced in the series to form an upholstery supporting upper surface for the spring support. These slats 28 are loosely confined against lateral displacement at their rear ends in connection with the rear floating rail 17 so that they may move in the direction of their lengths relative to said rail. For this purpose the rear end portions of the slats 28 may extend through the notches 29 of a notched bar 30 secured to the rail 17 along its upper surface as best seen by a comparison of Figs. 2 and 3. Thus each of the floating rails 16 and 17 may yield vertically independently of the other and both may similarly yield in unison. Likewise, lengthwise movement of the surface slats 28 with respect to at least one of the rails

permits these slats to yield vertically without necessitating vertical yielding of either rail.

The spring supporting structure above described in respect to the seat frame of furniture, may be duplicated in connection with the back frame as plainly seen in Fig. 1. In this connection the floatingly supported rails 16a and 17a are seen respectively as upper and lower rails, with relatively inclined supporting spring slats 18a and 19a secured at their outer ends thereto and connected at their inner abutting ends to anchor blocks 20a by means of cap blocks 26a. The series of slats 28a forming the upholstery supporting surface of the spring support, will be secured to the upper rail 16a and their relatively lengthwise movable connection with the lower rail 17a may be accomplished by a notched bar 30a on said lower rail, the same as described previously with respect to bar 30 of the seat support.

In the spring supporting structure as thus set forth, it is plain it may be pre-formed for either seat or back frames and secured in the seat and back frames by fastening the anchor blocks in place. This materially reduces the cost of assembly. Also the supporting spring slats 18, 18a, 19 and 19a may be straight, flat slats so that bending, steaming and other shaping operations are avoided without detracting from the natural resilience and comfortable yield of the spring support as a whole.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. A spring structure for seat and back frame of furniture, comprising a frame which includes spaced cross members and parallel side members, said side members having anchor blocks secured

thereto intermediate their length, said spring structure consisting of a pair of spaced parallel rails, a plurality of series of superposed leaves of varying lengths mounted upon and secured to said anchor blocks, each series of leaves being disposed on said blocks in abutting end to end and angular relation and cooperating to form a unitary spring structure, a cap block securing said leaves upon said anchor blocks; the longest leaf of each series being secured to and supporting said spaced parallel rails, a series of slats upon said rails, one end of said slats being firmly secured to the top of one of said rails and the other end of said slats resting freely upon and extending beyond the companion rail, and guide means on said companion rail and enclosing said slats near the ends thereof to space same and maintain their spaced relation during the flexing thereof.

2. A spring supporting structure for seat and back frames of furniture, including a front and a rear rail and frame sides, comprising a pair of spaced apart, parallel rail members, a plurality of series of spring members, the series being at opposite sides of the frame, the spring members in the respective series at corresponding sides of the frame being inclined with respect to each other and having their upper, outer ends securely fastened to said rails at and under the ends of the latter, blocks intermediate the length of and secured to said frame sides receiving the inner ends of the spring members, in abutting relation, blocks fastened to said spring members and said receiving blocks to anchor said spring members, and a series of upholstery supporting slats in spaced relation, each being securely fastened at one end to one of said rails upon the top thereof and each having its opposite end freely riding on the other rail, and a bar having notches in the lower face thereof, secured to said latter rail, the notches forming openings in which the free riding ends of said slats are disposed, to thus restrain said slat ends against lateral and vertical displacement relative to the respective rail.

WILLIAM A. KALPAKOFF.
